UNITED STATES PATENT OFFICE.

OTTO KELLNER, JR., OF CHICAGO, ILLINOIS.

LOOSE-LEAF BINDER.

No. 904,618.

Specification of Letters Patent.

Patented Nov. 24, 1908.

Application filed May 18, 1906. Serial No. 317,450.

To all whom it may concern:

Be it known that I, Otto KELLNER, Jr., a citizen of the United States, and a resident of Chicago, county of Cook, and State of Illinois, have invented certain new and useful Improvements in Loose-Leaf Binders, of which the following is a specification.

The invention relates to loose leaf and other temporary binders and seeks to provide an improved construction of metal ring for such binders for retaining the loose sheets of paper and the like within the covers of the binders.

The invention consists in the novel features of construction hereinafter described, illustrated in the accompanying drawings and more particularly pointed out in the appended claims.

In the drawings, Figure 1 is a perspective view of a loose leaf binder provided with the improved rings. Fig. 2 is a sectional view thereof. Fig. 3 is an edge view of the improved ring in open position. Fig. 4 is a similar view showing the ring in closed position.

The binder comprises the covers 10 of any suitable material, but preferably of stiff board, connected at their rear edges by a flexible back 11 of leather or like suitable material. The covers are provided adjacent their rear edges with eyelets 12 and the loose sheets 13 of paper or the like are held in place between the covers by the improved fastening rings 14 which extend through the eyelets 12 and through suitable openings formed in the rear edges of the loose sheets.

Each ring 14 comprises a single piece of wire formed of flexible spring metal—preferably mild steel. The wire of which the ring is formed is preferably round in section and of small diameter, so that it is flexible to permit the opening of portions of the ring. The wire is bent to circular form with its free ends in offset relation, as shown in Fig. 3. The remote or outer faces of the ends of the ring are provided with outwardly facing, interlocking lugs 15 and notches 16. The lugs and notches on the opposite ends of the ring are of similar form and so shaped that when interlocked, as shown in Figs. 1, 2 and 4, a continuous closed ring of uniform section is formed.

In the open position of the ring shown in Fig. 3, its ends are normally held in offset relation with the interlocking lugs and notches on their outer or more remote faces.

The ends of the ring are movable against the tension of the spring metal body of the ring, first in axial direction past each other and then in circumferential direction to their overlapped interlocked position shown in Fig. 4. Both the axial and circumferential movements of the ends of the ring, which are necessary to interlock the same, take place against the tension of the spring metal body of the ring, so that when its ends are interlocked the ring is positively placed both under a torsional and an expansive strain or stress which is then exerted in keeping the ends firmly interlocked.

The invention thus provides a simple form of ring which may be very cheaply manufactured, which may be easily opened for insertion into the binder and readily closed to prevent displacement of the sheets or the like between the covers of the binder. When the free ends are interlocked a closed ring is formed of uniform circular section which will readily slide through the eyelets of the covers and through the openings in the sheets of paper or the like between the covers. Moreover, the ring is locked under expansive and torsional strain which is exerted to hold the ends of the ring interlocked and prevents accidental opening of the ring. As stated, the metal of the ring is of small size so that its ends may be flexed or bent apart, as indicated in dotted lines in Fig. 3, if desired, for more ready insertion through the eyelets 12 of the covers and through the openings of the sheets or leaves 13. Such a flexure of the ring merely increases the torsional strain against which its ends are interlocked and against which the ends are brought together and which serves to hold the same in interlocked position. With the improved construction rings of small size for small loose leaf binders may be conveniently manufactured.

Having described my invention, what I claim as new and desire to secure by Letters Patent, is:

1. A metal ring for loose leaf binders and the like formed of a single, continuous piece of flexible spring wire having its ends in open position spaced apart both in axial and circumferential direction with their outer or remote side faces provided with interlocking lugs and notches, said ends being movable against the tension of the spring metal body of the ring in axial direction past each other and in circumferential direction.

- to overlapped, interlocked position, as described, whereby the metal body of the ring is placed under torsional and expansive stress to hold the ends securely interlocked.
- 5 2. In loose leaf or temporary binders, the combination with the covers having eyelets adjacent one edge, of metal rings extending through said eyelets, each formed of a single piece of flexible spring wire of uniform cross-section having its ends spaced apart both in axial and circumferential direction with their outer or remote side faces cut away and provided with interlocking lugs
- 10 and notches, said ends being movable against the tension of the spring metal body of the rings, first axially past each other and then circumferentially to overlapped, interlocked position, to form a closed ring of uniform circular cross-section, whereby said rings are placed under torsional and expansive strain 20 to hold their ends securely interlocked.
